UNITED STATES PATENT OFFICE.

FREDERICK C. EHRENBURG AND THEODOR EHRENBURG, OF NEW YORK, N.Y.

IMPROVEMENT IN WINDING-MACHINES.

Specification forming part of Letters Patent No. 123,251, dated January 30, 1872.

To all whom it may concern:

Be it known that we, FREDERICK C. EHRENBURG and THEODOR EHRENBURG, of the city, county, and State of New York, have invented a new and Improved Thread-Winding Machine; and we do hereby declare the following to be a full, clear, and exact description thereof, which will enable those skilled in the art to make and use the same, reference being had to the accompanying drawing forming part of this specification, in which drawing—

Figure 1 represents a side view of this invention. Fig. 2 is a longitudinal vertical section of the same. Fig. 3 is a plan or top view of the same.

Similar letters indicate corresponding parts.

This invention relates to certain improvements in winding-machines of that class which we have described in our patent No. 76,724, dated April 14, 1868; the principal object of our improvements being to adapt our machine to the operation of winding thread or yarn on bobbins in the form of cops. This present invention consists in the arrangement of the V-shaped cop-gauge, the sliding carriage which carries it, the hinged bobbin-frame, the tappet-rod, the yarn-guide, and the devices for operating the two last-named parts and the stop-lever or belt-shifter, as hereinafter described, so that, as the bobbin fills up the cop, the gauge and carriage recede, whereby the desired shape of the cop is insured, so that, when the cop is finished, the machine is stopped automatically, to allow the removal of the finished cop and the readjustment of the machine for the next one; further, in the arrangement, on the carriage containing the yielding cop-gauge, of a hinged oscillating thread-guide, a cam which actuates the thread-guide, and a worm-wheel, which actuates the cam, and which receives motion from a screw-thread on the main shaft, in such a manner that the thread-guide retains its proper relative position to the cop-gauge throughout the whole operation, and that the thread is laid on evenly from one end of the cop to the other.

In the drawing, the letter A designates a bed-plate provided with a bracket, B, by means of which the machine is secured to a bench or other suitable support. From the bed-plate

A rise two standards, C C', which form the bearings for the driving or main shaft D. To one of these standards, C', is connected, by a hinge-joint, a, a yoke or frame, E, which forms the bearings for an arbor, b, which is intended to receive the spool. On said arbor is mounted a pinion, c, which, when the spool-frame is turned down to its working position, meshes into a cog-wheel, d, mounted on the main shaft D, and a weight, e, which is secured to the arbor b or to the spool-frame, serves to keep the pinion in gear with the cog wheel. To said arbor is secured a collar, f, from which projects a pin, g, that catches in a hole in the end of the bobbin, (see Fig. 2,) so that the bobbin, when placed on the arbor, is compelled to rotate with the same. The spool-frame is hinged, so that it can be turned up to a vertical position, for the purpose of facilitating the introduction and the removal of the bobbins. The main shaft D forms the guide for a carriage, F, the bottom end of which travels in grooved ways G, formed in a projection of the bed-plate A. From the top of this carriage extends the V-shaped cop-gauge H, and from the bottom part of the carriage projects an arm, I, which forms the bearing for the pivot h of the lever J, which carries the thread-guide i. The lever J is made in the form of a bell-crank, and to its horizontal arm is secured a weight, j, which serves to keep a roller, k, mounted on the vertical arm of said lever, in contact with a cam, K, that serves to impart to the thread-guide the required reciprocating motion to lay the thread evenly upon the bobbin. The cam K is mounted loosely on a pin, l, which is secured in an arm, L, projecting from the carriage F, and on the hub of said cam is firmly secured a worm-wheel, m, which gears in a screw-thread, n, cut on a portion of the main shaft D. As the main shaft revolves, a slow revolving motion is imparted to the cam K, and by the action of this cam the required reciprocating motion is given to the thread-guide. The carriage F is pressed inward over the bobbin by the action of a spring, M, which may be coiled round the end of the main shaft, as shown in the drawing, or which may be applied in any other desirable manner. As the bobbin fills up, the thread acts against the

V-shaped cop-guide, and the carriage F is gradually forced back in the direction of the arrow marked on it in Fig. 1. To the outer end of the pin l, which forms the bearing for the cam K and worm-wheel m, is firmly secured a collar, o, from which projects a pin, p, and, as the carriage is forced back in the direction of the arrow marked on it in Fig. 1, said pin catches under the inclined edge of a tappet, N, which is secured on a rod, P, that is hinged to the shipper or stop-lever Q. In the drawing we have shown a lever, Q, which is hinged to the bed-plate, and which is provided with a projection to catch in an annular groove, q, formed on the outer end of the driving-pulley R. This driving-pulley slides on the main shaft, and its inner end is made in the form of a clutch, to engage with a pin, r, secured in the main shaft, whenever the lever Q is brought in the position shown in Fig. 1. This lever is subjected to the action of a spring, S, which has a tendency to throw the same back in the direction of the arrow marked on it in Fig. 1; and if the lever is permitted to follow the action of this spring the pulley R is carried out of gear with the clutch-pin r and the motion of the shaft D stops. The tappet-rod P is provided with a notch, s, (see Fig. 1,) which can be thrown in gear with a pin, t, secured to an arm projecting from the standard C', and by these means the stop-lever Q is retained against the action of its spring, and the pulley R is kept in gear with the clutch-pin r. But, as the carriage F is forced back by the action of

the thread which fills the bobbin, the pin p, by its action on the tappet N, gradually raises the rod P, and, by the time the bobbin is full, the notch of the tappet-rod is lifted out of gear with the pin t, the stop-lever flies back, and the motion of the machine stops.

It is obvious that the stop-lever Q might be made in the form of a belt-shipper without changing the result. By this arrangement we are enabled to fill bobbins in the form of cops, and the whole operation can be effected in a simple and easy manner, requiring no practiced or experienced labor.

What we claim as new, and desire to secure by Letters Patent, is—

1. The combination of the sliding carriage F, V-shaped cop-gauge H, hinged frame E, yarn-guide j, cam k, collar o, pin p, tappet-rod P, and stop-lever or belt-shifter Q, all arranged and operating substantially as and for the purpose set forth.

2. The arrangement, on the carriage containing the yielding cop-gauge, of a hinged oscillating thread-guide, a cam K, and a worm-wheel, m, engaging with a screw-thread on the main shaft, substantially in the manner herein described, so as to keep the thread-guide always in the proper relation to the cop-gauge.

F. C. EHRENCBERG.
THEODOR EHRENCBERG.
